(57) **CLAIM**

I claim, the ornamental design for a knitting needle, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a side view of a knitting needle showing the new design;

FIG. 2 is another side view of the knitting needle shown in a second color scheme;

FIG. 3 is another side view of the knitting needle shown in a third color scheme; and,

FIG. 4 is another side view of the knitting needle shown in a fourth color scheme.

**1 Claim, 4 Drawing Sheets
(4 of 4 Drawing Sheet(s) Filed in Color)**
